UNITED STATES PATENT OFFICE.

ARLON LITTLEFIELD, OF CRANSTON, RHODE ISLAND, ASSIGNOR TO NEW ENGLAND BUTT COMPANY, OF PROVIDENCE, RHODE ISLAND, A CORPORATION OF RHODE ISLAND.

BRAIDING-MACHINE.

1,389,672.

Specification of Letters Patent.

Patented Sept. 6, 1921.

Application filed January 15, 1920. Serial No. 351,629.

To all whom it may concern:

Be it known that I, ARLON LITTLEFIELD, a citizen of the United States, and resident of the city of Cranston, in the county of Providence and State of Rhode Island, have invented certain new and useful Improvements in Braiding-Machines, of which the following is a specification.

This invention relates to improvements in the construction of braiding machines; and has for its object to provide an improved braiding-machine frame which is composed of a plurality of standards mounted on the body portion of the machine on which standards is removably and adjustably mounted one or more cross bars arranged to support a portion of the operating mechanism of the machine in such a way that the mechanism is readily removable and the parts thereof interchangeable.

With these and other objects in view, the invention consists of certain novel features of construction, as will be more fully described, and particularly pointed out in the appended claims.

In the accompanying drawing:

Figure 1— is a perspective view illustrating my improved frame as mounted on the body of a braiding machine, said frame carrying one style of head and its coöperating mechanism.

Fig. 2— is an elevation illustrating a modified form of the frame-work of the machine with some of its interchangeable parts.

Fig. 3— is a side elevation illustrating a style of head different from that shown in Fig. 1, but equally well supported by the same adjustable frame members of the machine.

Fig. 4— is a side elevation showing the arrangement of the bearing members on one of the side standards for supporting the upright take-up drive shaft and its operating mechanism, also showing a bearing for a second parallel cross-bar.

In practice many different styles of take-up and take-off heads and their component or coöperating parts are employed in braiding machines having otherwise the same general design and arrangement of mechanism in their body portions. In ordering a machine of a given type some users require heads and parts of one style for the production of a certain class of work, while others require a head and parts of another style of

take-up or take-off mechanism and its coöperating parts to produce certain other classes of work, and therefore, it is found to be of great advantage to be able to make all of the parts interchangeable so that any particular style or type of take-up or take-off head mechanism and its coöperating parts may be positioned on the frame without being obliged to make special arrangements or a special construction to accommodate the particular style desired. In other words, the parts of the frame and the operating mechanism carried by the frame are so constructed as to render the mechanism readily detachable and interchangeable.

The following is a detailed description of one form of mechanism by which I am enabled to accomplish the desired results:

With reference to the drawing, 10 designates one of the plates of the body portion of a braiding machine, which is supported on the usual legs 11. On this body portion is mounted a simple, inexpensive and practical form of frame which is adapted to support the upper operating mechanism of the machine such as the take-up and take-off heads and other parts which are employed in the controlling of the braid after it has been formed, or any other mechanism which may be mounted there. To accomplish this in a simple and practical way, I have provided two side standards 12, preferably of finished rods of the cold rolled type, which are reduced and threaded at their lower ends 13 to pass through corresponding holes in the plate 10 and be secured thereto, each by the means of a nut 14. I have also provided a standard 15 in the rear of the machine or between the side standards, which is secured to the plate 10 by a nut 16. On the upper end of each of these standards I have mounted removable bearing members 17, 18 and 19 respectively, which are adjustably and removably secured in position by means of a set screw 20, 21 and 22 respectively. These bearing members may be of any desired form to accommodate the different combinations of mechanisms adapted to be mounted on the frame. One purpose being to removably and adjustably support the main cross-bar 27 which is, like the standards, preferably formed of a finished rod and which is bound in these bearings 17 and 19 by set screws 28 and 29 respectively.

In addition to supporting the cross bar 27

I also provide a forwardly-extending arm 23 which has a bearing 24 adapted to support one end of the take-up-roll-driving shaft 25 and the driving gear 26. This arm is also shown as supporting a bearing 50 on which the upright take-up drive shaft 51 is mounted. The rest of this take-up mechanism is supported from an adjustable and readily removable arm 30 mounted on the bearing 31 on this side standard 12, which arm 30 serves as a second bearing 52 for said upright shaft 51.

In constructing the take-up heads to fit onto this frame, as illustrated in Fig. 1, I 15 preferably provide the head 32 with a body portion 33 bored to receive the cross bar 27 which passes therethrough, its rear end 34 being also bored transversely to receive the rear brace-bar 35, the rear end 36 of which 20 bar is adjustably mounted in the bearing 18 and secured by set screw 37, whereby this head is securely held in position on the main frame and yet is readily removable and interchangeable with other styles of heads and 25 parts. This head frame or body is provided with a pair of forwardly extending arms 38 in which is mounted the usual take-up rolls 39 around which is passed the braided cord 40 from whence it is led across to the delivery rolls 41 and down through the chute 42. These delivery rolls being supported on 30 an upright arm 43 which is adjustably mounted at 44 on the rear standard 15.

In some cases instead of employing the 35 style of head employed in Fig. 1, I employ that illustrated in Fig. 3, in which the take-up roll 45 is adjustably mounted on the arm 46 in the head 47 to regulate its bite against the roll 48. This head, like that illustrated 40 in Fig. 1, is mainly supported on the main cross bar 27 and is also provided with a rear socket portion 49 adapted to receive the rear brace-bar 35 in the head 18.

As all of these parts are formed interchangeable one head may be as readily positioned on the frame of the machine as another.

By my improved construction when the take-up parts are formed interchangeable, 50 the body of the machine may be readily changed over to receive any desired style of head; that is, after operating for a given length of time with one set of head parts it may be readily changed over and operated 55 with any other style of head parts, without disturbing or altering the main or body portion of the machine.

My improved mechanism greatly simplifies and lessens the cost of construction of 60 the different styles of machines as all of the parts are rendered removable and interchangeable and any style of take-up or take-off head or mechanism may be applied thereto.

65 In some cases such as in the construction of

light braiding machines I may omit the rear standard 15 and brace-bar 35 if desired and instead mount a second cross-bar 53 in the superposed bearings 54 in uprights 12, which second bar may also be passed through a 70 suitable second bearing or hole in the head frame, as illustrated in dotted lines at 55 in Fig. 2.

The foregoing description is directed solely toward the construction illustrated, 75 but I desire it to be understood that I reserve the privilege of resorting to all the mechanical changes to which the device is susceptible, the invention being defined and limited only by the terms of the appended 80 claims.

I claim:

1. In a braiding machine, a body portion including the braiding and twisting elements, a frame supported on said body comprising two side standards, a mechanism supporting cross-bar removably mounted on said side standards, a rear standard on the body portion of the machine and positioned between said side standards, and means 85 whereby said rear standard is caused to co-operate with said cross-bar for adjustably supporting said mechanism.

2. In a braiding machine, a body portion including the braiding and twisting elements, a frame supported on said body, comprising two side standards, a mechanism supporting cross-bar removably mounted on said side standards and connecting the same, a rear standard on the body portion of the 100 machine and positioned between said side standards, and a brace-bar removably mounted on said rear standard arranged to co-operate with said cross-bar for operatively supporting said mechanism, said cross-bar 105 and rear standard being adapted to removably and adjustably support take-up and take-off mechanisms, respectively, in co-operative relation.

3. In a braiding machine, a body portion 110 including the braiding and twisting elements, a frame supported on said body, comprising two side standards, a cross-bar removably mounted on bearings on said standard and connecting the same, a take-up head frame provided with a hole through which said cross-bar is adapted to pass to support the same, means for binding said head frame in adjusted position to said cross-bar, and a rear standard on the body 115 of the machine between said side standards and co-operating in the support of said head frame.

4. In a braiding machine, a body portion 120 including the braiding and twisting elements, a frame supported on said body, comprising two side standards, a cross-bar removably mounted on said standards and connecting the same, a take-up head frame provided with a hole therein through which 125

said cross-bar is adapted to pass to support the same, means for binding said head frame to said cross-bar, a rear standard on the body portion of the machine and positioned

5 between said side standards, a brace-bar removably mounted on said rear standard and engaging with said head frame to coöperate in the supporting of said head frame.

5. An attachment for braiding machines 10 comprising a frame including a pair of side standards one to be positioned on each side of the machine, a cross-bar removably mounted in said bearings on the upper end of said standards to over-lie the braid mechanism, said cross-bar being adapted to have a take-up mechanism mounted thereon, and another standard to be positioned on the rear of the machine between said side standards and to coöperate with said cross-bar for 15 supporting the mechanism mounted thereon, said rear standard being adapted to removably support a take-off mechanism to coöperate with said take-up mechanism.

6. An attachment for braiding machines 20 comprising a frame including a pair of side standards having removable and adjustable bearing members thereon, a cross-bar removably mounted in said bearings, said standards being adapted to be positioned 25 one on each side of the machine whereby the cross-bar will overlie the bearing mechanism of the machine, a head frame removably mounted on the cross-bar, another standard 30

to be positioned on the rear of the machine between said side standards and having a removable bearing member mounted on the upper end thereof, and a substantially horizontal brace-arm removably connecting said last mentioned bearing member and said head frame, for supporting the latter in position. 35

7. An attachment for braiding machines comprising a frame including a pair of side standards having removable and adjustable bearing members thereon, a cross-bar removably mounted in said bearings, said standards being adapted to be positioned 40 one on each side of the machine whereby the cross-bar will overlie the bearing mechanism of the machine, a head frame removably mounted on the cross-bar, another standard 45 to be positioned on the rear of the machine between said side standards and having a removable bearing member mounted on the upper end thereof, and a substantially horizontal brace-arm removably connecting said last mentioned bearing member and said head frame, for supporting the latter in position. 50

55 In testimony whereof I affix my signature.

ARLON LITTLEFIELD.
